UNITED STATES PATENT OFFICE.

HEINRICH CHRISTIANSEN, OF PINNEBERG, GERMANY.

PNEUMATICALLY-OPERATED PERCUSSION-TOOL.

1,227,117.

Specification of Letters Patent. Patented May 22, 1917.

Application filed October 26, 1916. Serial No. 127,830.

To all whom it may concern:

Be it known that I, HEINRICH CHRISTIANSEN, a citizen of the German Empire, resident at Pinneberg, in the Kingdom of Prussia, German Empire, have invented new and useful Improvements Relating to Pneumatically-Operated Percussion-Tools, of which the following is a specification.

This invention relates to pneumatically operated percussion tools actuated by reciprocating air-columns, such tools including percussion drills, pneumatic hammers, stamping tools for railways, and so forth.

A tool constructed according to the present invention is shown by way of example in the accompanying drawings, wherein:

Figure 1 shows a longitudinal section of a tool with the hammer-piston just striking the end of the tool proper, and

Fig. 2 shows a similar view with the hammer-piston in a position which it reaches when the tool meets with no resistance.

In such tools a reciprocating piston-hammer *b* is driven backward and forward in a cylinder *a* by connecting the spaces in front and behind the hammer-piston *b* by means of ports *c* and *d* and suitable piping to cylinder spaces in front of and behind a power driven reciprocating piston or pistons. The power-driven reciprocating piston and the hammer-piston *b* operated by the air-columns, moving to and fro between these pistons, therefore carry out corresponding movements. On the forward movement the hammer-piston *b* strikes the tool *e* and transmits its kinetic energy by this impact. The tool *e* is guided in the tool holder *g* which is mounted in the neck of the cylinder *a*. The tool *e* is provided with a collar *e'* which during the forward movement of the tool, first moves freely and then strikes against the front end of a spring *i* of which the rear end is secured, for example by being threaded on the neck of the cylinder. The spring *i* thus prevents the tool from being driven out in case the tool is not in contact with the work when the whole energy of the hammer-piston *b* is expended in the acceleration of the tool *e*.

In order to prevent the hammer-piston *b* from striking against the cylinder cover *f* at the end of its return stroke, the port *d* opens into the cylinder at *d'* some distance from the cylinder cover *f*. The hammer-piston *b* closes the opening *d'* of the port *d* during its return stroke. The closed

space behind the piston thus forms an air-cushion and prevents the impact of the piston *b* against the cover *f*. In the space in front of the hammer-piston such a cushioning effect must not take place as the kinetic energy of the piston must be completely utilized in the impact and no other resistance must be opposed to the forward movement of the piston than that of the work upon which the tool is to operate. Consequently the space in front of the hammer-piston must be continuously in communication with the space in front of the power-driven air piston which effects the reciprocation of the air-columns. The opening *c* of the port *c* must therefore be as near as possible to the front end of the cylinder and must not be closed by the hammer-piston during normal working.

According to the present invention the hammer-piston is automatically stopped in spite of the continued operation of the air piston which produces the movements of the reciprocating air-columns, as soon as the tool is no longer pressed against the work, and the hammer-piston *b* automatically recommences its operation as soon as the tool *e* is again pressed against the work. For this purpose the port *c* leading to the front cylinder space is provided, in addition to the opening *c'* at the front end of the cylinder, with a second opening *c''* disposed somewhat to the rear. This opening *c''* is disposed so far toward the rear that it is closed by the hammer-piston *b* when the piston has still a considerable portion of its stroke to complete, before it strikes the tool *e*. The air in front of the piston *b* communicates therefore during the last part of the stroke of the hammer-piston entirely through the opening *c'* with the space in front of the power-driven air-piston (see Fig. 1). When the tool *e* rests against the work, the said tool can only be driven forward a short distance, and the hammer-piston *b* can only be impelled forward through an equally short distance and therefore does not expose the opening *c''*. If however the tool *e* does not rest against the work, then it can be driven by the piston *b* to the position shown in Fig. 2. The piston *b* is then impelled forward such a distance that the opening *c''* is uncovered. The tool holder *g* is provided with a steel spring ring *h* over which the cylindrical boring in the front end of the hammer-piston *b* engages. It is then held by the

spring h in such a manner that the buffer action of the spring i can no longer move back the tool e and by means of this the piston b . The reciprocating air-columns whose movements are produced by the piston of the power-driven machine are now no longer separated by the piston b but communicate directly with one another through the port c , opening c^2 , the space behind the hammer-piston b , the opening d' , the port d and the connecting piping. The hammer-piston is therefore not operated although the power-driven piston continues to reciprocate. If however the tool e is again pressed against the work, the hammer-piston b is again returned to the position shown in Fig. 1, and must now again be operated by the power-driven piston through the medium of the reciprocating air columns.

10 20 The hammer-piston b is also not actuated but remains stationary in its forward position, uncovering the opening c^2 , when the tool e has been completely removed from the apparatus.

15 25 I claim:

30 35 40 45 1. A pneumatic percussion implement comprising a cylinder closed at its rear end, a hammer-piston within said cylinder, a tool and means for guiding it in the forward end of said cylinder, said cylinder having a port opening a short distance from the rear end thereof for the admission of fluid to drive the hammer-piston toward the tool and to produce an air-cushion on the return stroke of the hammer-piston, and a port having one opening in the cylinder at the front thereof and also another opening in the cylinder at a distance behind the front end of the cylinder slightly greater than the length of the hammer-piston, whereby the two cylinder ports are put into communication behind said piston, and the piston is rendered inoperative whenever the tool is not pressed against the work so as to oppose a resistance to the free forward movement of said tool and the piston.

50 55 60 65 70 2. A pneumatic percussion implement comprising a cylinder closed at its rear end, a hammer-piston within said cylinder, a tool and means for guiding it in the forward end of said cylinder, said cylinder having a port opening a short distance from the rear end thereof for the admission of fluid to drive the hammer-piston toward the tool, a port having one opening in the cylinder at the front thereof and also another opening in the cylinder at a distance behind the front end of the cylinder slightly greater than the length of the hammer-piston, whereby the two cylinder ports are put into communication behind said piston, and the piston is rendered inoperative whenever the tool is not pressed against the work so as to oppose a resistance to the free forward movement of said tool and the piston, spring means for preventing the ejection of the tool from the cylinder, and means for holding the hammer-piston in its forward inoperative position so long as the tool is not pressed into contact with the work.

75 80 85 90 3. A pneumatic percussion implement comprising a cylinder having means for the admission and outflow of the operating fluid, a tool guide mounted in the forward end of the cylinder, a tool mounted in said guide, a hammer-piston mounted for reciprocation in said cylinder, spring means on said guide for holding the piston in its forward inoperative position when the tool is not pressed back by the work, and by-passing means from one of the ports, said by-passing means being so arranged that the operating fluid can pass through the cylinder without operating the piston when the piston is held in the inoperative position.

In witness whereof I have hereunto set my hand in presence of two witnesses.

HEINRICH CHRISTIANSEN.
